UNITED STATES PATENT OFFICE.

MILLICENT HOGG AND JOSEPH C. DE HAVEN, OF LOS ANGELES, CALIFORNIA.

DESIGN FOR AN ORNAMENT FOR MOTORMETERS.

Application filed September 28, 1925. Serial No. 14,920. Term of patent 3½ years.

To all whom it may concern:

Be it known that we, MILLICENT HOGG, a citizen of Canada, and JOSEPH C. DE HAVEN, a citizen of the United States, both residents of Los Angeles, county of Los Angeles, State of California, have invented a new, original, and ornamental Design for Ornament for Motormeters, of which the following is a specification, reference being had to the accompanying drawing, forming part hereof.

The figure is a perspective view of an ornament for a motormeter, showing our new design.

We claim:

The ornamental design for an ornament for motormeters, as shown.

MILLICENT HOGG.
JOSEPH C. DE HAVEN.
